CONTAINER AND CLOSURE THEREFOR

Gustave Glocker, Washington, D. C., assignor to
Super-Seal Container Corporation, Washington, D. C., a corporation of Delaware

Application November 29, 1939, Serial No. 306,746

7 Claims. (Cl. 215—40)

This invention relates to so-called self-sealing containers adapted to be maintained in sealed condition solely by atmospheric pressure, of the general type shown in my Patent No. 2,187,396.

Heretofore a relatively precise fit between the lid, the sealing gasket, and the container mouth, constituting the primary elements of such combinations, has been required. These precise requirements have given rise to serious manufacturing difficulties and often resulted in the construction of containers which were unsatisfactory in service.

It is the broad object of this invention to provide a construction which eliminates the necessity of providing a precise interfitting of the several parts. It is also an object of the invention to provide such constructions which have inherent therein improved sealing characteristics.

These broad objects of the invention are attained by providing a lid for the open mouth of a container and a gasket or sealing member adapted to be carried by such lid, such sealing member having a leading edge extending beyond the main body thereof which affords a relatively narrow line area for contact with an annular shoulder provided internally of the container near the mouth thereof. The construction eliminates the necessity of precise interfitting and provides a clearance between the outer surface of the sealing member and the adjacent wall of the container at the mouth thereof. The use of clearance between the lid and the container mouth which permits irregularities in the lid, the sealing member, and the container mouth, is made possible by the improved sealing effect secured by the leading edge of the sealing member maintaining its relatively narrow line contact throughout the entire circumferential area of the shoulder at the mouth of the container.

Other objects of the invention and corresponding advantages inherent therein will become apparent as the detailed description is read with reference to the accompanying drawings in which:

Figure 1 is a vertical sectional view through a lid adapted to close the mouth of a container;

Figure 2 is a fragmentary vertical sectional view through the body of a container showing the open mouth at one end thereof;

Figure 3 is a fragmentary vertical sectional view through the lid and container showing the position of the lid on the open mouth of the container prior to the sealing thereof;

Figure 4 is a fragmentary vertical sectional view of the lid and container shown in Figure 3

after the same has been subjected to a sealing operation;

Figure 5 is a bottom plan view of the lid;

Figure 6 is an enlarged fragmentary sectional corresponding to Figure 3;

Figure 7 is an enlarged fragmentary section corresponding to Figure 4;

Figure 8 is an enlarged fragmentary section of a lid and container structure of a modified form; and

Figure 9 is an enlarged fragmentary section of a still further modified construction.

In the drawings, wherein like reference numerals indicate like parts, is shown a container 15 comprising a body portion 10, which is provided with a mouth having a wall 12 terminating in an annular shoulder 14 which is adapted to seat the end of a sealing member carried by the lid. The lid 16 has an annular groove 18 spaced inwardly from the peripheral edge. The groove 18 is adapted to seat the outer end of a sealing member. A sealing member 20 has its outer end 22 seated in the groove 18. The proportions of the sealing member 20 are such as to provide a snug fit between the outer faces thereof and the side walls of the lid which define the groove 18.

The lid 16 is provided with a backing wall 24 which depends from the body of the lid and the outer wall of which may define the inner wall 30 of the groove 18. The backing member 24 is adapted to afford support to the sealing member 20 throughout a major portion of its area.

The inner end 26 of the sealing member 20 is provided with a leading edge 28 which normally extends beyond the body of the sealing member and beyond the inner end of the backing member 24 to adapt said leading edge to contact the annular shoulder 14 prior to contact of the outer side 30 thereof with the wall 12 at the mouth of 40 the receptacle during sealing operations.

The position and the width of the groove 18 in the lid 16 are so arranged with respect to the walls at the mouth of the container to provide a slight clearance between the outer face 30 of the sealing member 20 and the wall 12 defining the mouth of the container.

The construction as described permits effective sealing of a container upon at least partial evacuation of its interior after the lid has been applied to the mouth of the container. In Figure 3 of the drawings is shown the manner in which the lid 16, the sealing member 20, and the walls 12 and 14 at the mouth of the container 10, co-operate upon placement of the lid upon the mouth 55 of the container prior to a sealing operation

which may consist of the partial evacuation of air from within the container.

By reference to Figures 3 and 6, it will be seen that the outer leading edge 28 at the inner end 26 of the sealing member 20 is in contact with the annular shoulder 14 in such manner as to provide a relatively narrow line contact around the entire circumference of the annular shoulder 14. At the same time, it will be noted that a small annular space remains between the outer face 30 of the sealing member 20 and the mouth defining wall 12 of the container.

Upon contact of the leading edge 28 with the annular shoulder 14, an immediate seal is provided between the cover 16 and the container 10. This relatively narrow line annular seal functions effectively as a valve during the egress of air and vapors from within the container. The ebullition of hot substance within the container or substance heated in the container will be effective to lift the lid 16 sufficiently to permit escape of air and vapors from within the container. Upon the escape of such air and vapors, and upon the release of internal pressure otherwise, the lid 16 will return immediately and under its own weight to the position wherein the leading edge 28 again contacts throughout the circumference of the annular shoulder 14 to form an effective seal.

The free movement during the placement of the lid 16 upon the mouth of the container 10 and during the escape of air and vapor from the interior of the container 10 is permitted by the clearance provided between the outer face 30 of the sealing member 20 and the oppositely disposed wall 12 defining the mouth of the container. This clearance insures, among other things, that the sealing member 20, and particularly the leading edge 28 thereof, is seated against the shoulder 14 at all times. The clearance eliminates all possibility of improper seating of the cover 16 on the mouth of the container.

The still greater consideration of manufacturing convenience is secured by providing the clearance between the face 30 of the sealing member 20 and the wall 12 of the container. It is difficult to provide molded articles of the very precise form and dimensions required by self-sealing containers of the type heretofore known. The present construction makes it possible to manufacture by simple and speedy molding operations, containers and covers therefor, while directing a minimum amount of attention to the perfect formation thereof. Similarly, precise dimensions and surface characteristics of the sealing member 20 need not be achieved, because of the construction herein which provides the clearance between the sealing member and the side wall of the container mouth which will compensate for slight irregularities in the container mouth, the lid, or the sealing member.

Figures 6 and 7 contrast the position of the lid 16 with respect to the mouth of the jar and the shape and position of the sealing member 20 with respect to the container and lid walls adjacent thereto, after the initial placement of the lid 16 on the mouth of the container 10, on the one hand, and on the other hand, the sealed condition of the container after it has been at least partially evacuated and atmospheric pressure has become effective to hold the lid 16 so tightly on the mouth of the container 10 as to deform the elastic sealing member 20 against the adjacent walls of the lid and container to form an effective seal. The seal thus achieved is maintained until the same has been deliberately broken and

atmospheric pressure has been admitted to the interior of the container.

In order to release the lid 16 after the same has once been firmly seated upon the mouth of the container 10, there has been provided a passageway extending through the zone occupied by the sealing member 20, such passageway being adapted to receive and guide a piercing tool effective to permit ingress of atmosphere.

10 In Figure 5 of the drawings, is shown a recess 34 which is formed in the underside of the peripheral flange of the lid 16. This passage 34 is located at a point below the bottom of the groove 18 and in alignment with a passage 36 formed by the depending wall 24. The passage 36 opens downwardly into the container 10 when the lid is applied thereto for the purpose of permitting the free flow of external atmosphere through the passage 34 and into the container when the sealing member 20 has been pierced by any suitable piercing instrument.

15 The objects and advantages of the invention can be secured by other embodiments of the invention which include the several essential characteristics. For example, in Figure 8 of the drawings, is shown a lid wherein a sealing member backing flange 44 has a face 46 which depends substantially in a perpendicular direction with respect to the horizontal plane of the lid. In the form of the invention first described, the wall of the depending flange 24 which lies in contact with the sealing member 20 is formed on an inwardly extending bevel. The bevel of the sealing member supporting surface is effective to bias the sealing member 20 sufficiently to project the outer edge 28 at the inner end thereof as shown in Figure 6. In the form of the invention illustrated in Figure 8, wherein the wall 46 of the backing member 44 is substantially perpendicular to the horizontal plane of the lid, there is no biasing influence on the backing member 44, and consequently the sealing member 20 must be provided with a leading edge and this can be done by cutting the inner end of the sealing member on an angle so as to form thereon an edge 48 which extends beyond the body thereof.

20 In order to adapt the form of the sealing member to quantity production, it may be necessary to form the inner and the outer end thereof on the same angular cut. In such case the bottom wall 50 of the groove 18 in the lid 16 may be formed at a complementary angle to receive the angularly formed outer end of the sealing member, as shown in Figure 9.

25 It is to be understood that the sealing member 20 is formed of resilient material so that the same will deform readily upon the application of pressure to the lid. Furthermore, while the leading edge at the inner end of the sealing member has been illustrated and described as being located at the outer edge thereof, it is obvious that the important feature is the provision of a leading edge providing a narrow line contact with the annular shoulder 14, and that this edge may be located either at the inner or the outer side of the sealing member, or indeed, at any intermediate point thereof.

30 The embodiments of the invention have been illustrated and described for the purpose of teaching the broad features thereof and it is obvious that many modifications may be made without departing from the spirit of the invention, and it is understood that changes in the specific construction which do not depart from

the spirit of the invention fall within the meaning of the subjoined claims.

I claim:

1. A container comprising a body having a mouth provided with a wall terminating in an annular shoulder disposed substantially perpendicularly to said body internally of said container, a lid for said container having means adapted to seat the end of a sealing member, a sealing member of substantial rectangular cross section having its outer end seated by said means, a backing member depending from said lid adapted to support the inner side of said sealing member through a major portion of its area, the diameter of the wall at said mouth being sufficiently greater than the outside diameter of said sealing member to provide a substantial space between the adjacent surfaces thereof, and said sealing member having a leading edge at the inner end of said sealing member adapted to contact said annular shoulder in sealing engagement prior to contact of the outer side thereof with the wall at said mouth during sealing operations.

2. A container comprising a body having a mouth provided with a wall terminating in an annular shoulder disposed substantially perpendicularly to said body internally of said container, a lid for said container, having means adapted to seat the end of a sealing member, a sealing member of substantially rectangular cross section having its outer end seated by said means, a backing member depending from said lid adapted to support the inner side of said sealing member through a major portion of its area, the diameter of the wall at said mouth being sufficiently greater than the outside diameter of said sealing member to provide a substantial space between the adjacent surfaces thereof, and an outer edge at the inner end of said sealing member extending beyond the body thereof to adapt the same to contact said annular shoulder in sealing engagement prior to contact of the outer side thereof with the wall at said mouth during sealing operations.

3. A container comprising a body having a mouth provided with a wall terminating in an annular shoulder disposed substantially perpendicularly to said body internally of said container, a lid for said container having means adapted to seat the end of a sealing member, a sealing member of substantially trapezoidal cross section having its outer end seated by said means, and a backing member depending from said lid adapted to support the inner side of said sealing member through a major portion of its area, said wall at said mouth having a diameter sufficiently greater than the outside diameter of said sealing member to provide a substantial space between adjacent surfaces thereof, the longer side of said sealing member extending downwardly to provide a leading edge at the inner end thereof adapted to contact said annular shoulder in sealing engagement prior to contact of the outer side thereof with the wall at said mouth during sealing operation.

4. A container comprising a substantially cylindrical body having a mouth provided with a wall terminating in an annular shoulder disposed substantially perpendicularly to said body internally of said container, a lid for said container having means adapted to seat the end of a sealing member, a sealing member of substantially trapezoidal cross section having its outer end seated

by said means, and a backing member depending from said lid adapted to support the inner side of said sealing member through a major portion of its area, the outer side of said sealing member being longer than the inner side thereof to provide a leading edge at the inner end thereof, and a clearance between the outer side of said sealing member and the wall at said mouth to permit the free movement of said leading edge into sealing contact with said shoulder prior to contact with said wall during sealing operations.

5. A container comprising a body having a mouth provided with a wall terminating in an annular shoulder disposed substantially perpendicularly to said body internally of said container, a lid for said container having means adapted to seat the end of a sealing member, a sealing member of substantially trapezoidal cross section having its outer end seated by said means, and a backing member depending from said lid adapted to support the inner side of said sealing member through a major portion of its area, the diameter of the wall at said mouth being sufficiently greater than the outside diameter of said sealing member to provide a substantial space between the adjacent surfaces thereof, said sealing member having its inner end bevelled to provide a leading edge adapted to contact said annular shoulder in sealing engagement prior to contact of the outer side thereof with the wall at said mouth during sealing operations.

6. A container comprising a substantially cylindrical body having a mouth provided with an inwardly bevelled wall terminating in an annular shoulder disposed substantially perpendicularly to said body internally of said container, a lid for said container having means adapted to seat the end of a sealing member, a sealing member of substantially rectangular cross section having its outer end seated by said means, an inwardly bevelled backing member depending from said lid adapted to support the inner side of said sealing member and bias said sealing member to cause the outer edge at the inner end thereof to extend beyond the inner edge, and a clearance between the wall at said mouth and the outer side of said sealing member permitting said extending edge to contact said shoulder in sealing engagement prior to contact of the outer side thereof with said wall during sealing operations.

7. A container comprising a body having a mouth provided with a wall terminating in an annular shoulder disposed substantially perpendicularly to said body, a lid for said container having means adapted to seat the end of a sealing member, a sealing member having substantially parallel surfaces defining inner and outer sides joined by walls defining the outer and inner ends thereof, said sealing member having its outer end seated by said sealing member seating means, a backing member depending from said lid adapted to support one side of said sealing member through a major portion of its area, the diameter of the wall at said mouth and the diameter of the adjacent surface of said sealing member being sufficiently different to provide a substantial space between the adjacent surfaces thereof, and a leading edge at the inner end of said sealing member adapted to contact said annular shoulder in sealing engagement prior to contact of the surface thereof with the adjacent wall at said mouth during sealing operations.

GUSTAVE GLOCKER.
